(57) **CLAIM**

The ornamental design for a bag, as shown and described.

DESCRIPTION

FIG. 1 is a Top, Left and Front perspective view with lower part of bag unclaimed.

FIG. 2 is a Front elevation view with lower part of bag unclaimed.

FIG. 3 is a Rear elevation view with lower part of bag unclaimed.

FIG. 4 is a Left side elevation view with lower part of bag unclaimed.

FIG. 5 is a Right side elevation view with lower part of bag unclaimed.

FIG. 6 is a Top plan view with lower part of bag unclaimed.

FIG. 7 is a Bottom plan view with lower part of bag unclaimed.

FIG. 8 is a Top, Left and Front perspective view with the top of the bag open and with the lower part of bag unclaimed; and,

FIG. 9 is a Top, Right and Front perspective view with the top of the bag open and with the lower part of bag unclaimed.

The dash-dash broken lines depict unclaimed portions of the bag and stitching. The dot-dash broken lines disclose boundaries of the claimed design. All broken lines form no part of the claimed design.
